UNITED STATES PATENT OFFICE.

JAMES LIVINGSTON, OF PHILADELPHIA, PENNSYLVANIA.

WOVEN FABRIC.

SPECIFICATION forming part of Letters Patent No. 681,126, dated August 20, 1901.

Application filed March 7, 1901. Serial No. 50,188. (No specimens.)

To all whom it may concern:

Be it known that I, JAMES LIVINGSTON, a citizen of the United States, residing in Philadelphia, Pennsylvania, have invented certain 5 Improvements in Woven Fabrics, of which the following is a specification.

The object of my invention is to produce a woven fabric having chenille figures distributed throughout the same in close imitation 10 of figures produced by hand embroidery, these figures by preference appearing alike on both faces of the fabric and the method of weaving adopted being a simple one whereby figures of any desired coloring or shading may be 15 readily produced.

In the accompanying drawings, Figure 1 is a view of a piece of fabric made in accordance with my invention. Fig. 2 is a transverse section of the same—that is to say, a section 20 taken in the direction of the weft-threads—and Fig. 3 is a view of a piece of weft-thread such as is employed by me in weaving my improved fabric.

The fabric shown in Fig. 1 is composed of 25 warp-threads 1 and weft-threads 2, interwoven in any ordinary manner so as to produce a gauze, open-work, or leno fabric, the weft-threads 2 having at appropriate intervals bunches or tufts of chenille yarn, which in the 30 completed fabric are so disposed with reference to each other as to produce the desired figures 3, which may be either plain or may be as elaborately colored as desired, depending upon the coloring of said tufts of chenille 35 yarn. In producing these weft-threads the strands 2 are used as warp-threads in an ordinary chenille-weaving loom and are interwoven with the chenille-weft threads; but instead of weaving a continuous fabric, as usual,

40 said chenille-weft threads are introduced, so as to form strips or bands with intervening spaces formed by taking up any desired length of the warp-threads without inserting any of the chenille-weft threads, the result when the 45 fabric is severed between successive warp-threads being a series of threads or strands such as shown in Fig. 3, in which the chenille-threads are disposed in bunches or tufts 4 with intervening clear spaces 5, the bunches 50 or tufts being so related that when the thread or strand is used as a weft-thread in weaving the final fabric the bunches or tufts of che-

nille in successive picks will bear such relation to each other as to form the desired figures upon the fabric, these figures appearing 55 the same upon both faces of the fabric owing to the open-work or gauze character of the body of the fabric. When a double-faced fabric is not desired, however, a backing fabric of any appropriate character may be combined with the face fabric having the chenille 60 figures thereon.

The adoption of the gauze-weave prevents the beating up of the weft-threads so closely as to render too compact the chenille-carrying 65 portions of the same. Hence the chenille figures have the soft loosely-woven qualities characteristic of ordinary chenille goods, the fabric having substantially the same effect as though the figures were produced by hand 70 embroidery.

While the gauze-weave is preferable, it is not essential to the proper carrying out of my invention, since a plain weave could be adopted if there was sufficient take-up of the warp- 75 threads between successive picks of weft-thread to insure space for the reception of the chenille-carrying portions of said weft-thread without undue beating up of the figures formed thereby. In some cases, moreover, 80 the strands having the spaced or separated tufts of chenille thereon may be used as warp-threads instead of weft-threads, although the latter can be long enough for one repeat of the pattern, whereas if used as warp a much 85 greater number of strands would be required and the operation of weaving the fabric would be more complex.

Having thus described my invention, I claim and desire to secure by Letters Patent—

1. A fabric composed of interwoven warp and weft threads and having chenille figures separated from each other by an intervening open or lace-like ground, the figures being 95 formed by tufts of chenille yarn disposed at intervals upon one of said threads.

2. A fabric composed of interwoven warp and weft threads and having chenille figures separated from each other by an intervening 100 open or lace-like ground, the figures being formed by tufts of chenille yarn disposed at intervals upon said weft-threads, substantially as specified.

3. An open-work or gauze fabric composed of interwoven warp and weft threads and having chenille figures thereon, the warp-threads being twisted between the weft-threads and the latter threads having tufts or bunches of chenille yarn at intervals thereon, which form the chenille figures, substantially as specified.

In testimony whereof I have signed my name to this specification in the presence of two subscribing witnesses.

JAMES LIVINGSTON.
